UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

METAL TYPE.

No. 853,540.

Specification of Letters Patent.

Patented May 14, 1907.

Application filed December 12, 1905. Serial No. 291,442.

To all whom it may concern:

Be it known that I, JOSEPH S. DUNCAN, a citizen of the United States, residing at Chicago, in the county of Cook and State of Illinois, have invented new and useful Improvements in Metal Type, of which the following is a specification.

The object of this invention is to make a cast metal type light in weight and constructed to facilitate the setting up operation in the type groove of a type holder.

In the accompanying drawings illustrating one embodiment of the invention Figure 1 is a face view of my improved type. Fig. 2 is a 15 sectional view showing the type in the type groove of a type holder. Fig. 3 is a bottom plan view of the type. Fig. 4 is a face view of two type in a type holder. Fig. 5 shows another way of making the type. Fig. 6 is a 20 sectional view on the line 6—6 of Fig. 4.

Referring to the drawings the type A has a skeleton body formed by the two legs B, B, the web C and the top D. This web may be located centrally of the body as shown in Fig. 25 3 or at one side of the center as shown in Fig. 5. The top is preferably recessed at d, d between the legs B so that a space E will be provided between each pair of type when set up in the groove F of a type holder G and in 30 the supply channel.

My improved type will greatly facilitate the operation of moving type from a type channel of a type supply into a type groove of a type holder, for the instrument or device 35 which is used to move the type can always be inserted from beneath the type into the hollow body or from above or beneath the type into the space E between each pair of type. This is a distinct advantage over forcing the 40 moving instrument or device between type

which fit snugly together and contact throughout their adjacent faces, for in such case the instrument or device may injure the type and the operation is at all times difficult and slow. But where type are provided, as herein shown and described, with spaces for the reception of the moving instrument or device, the danger of injuring the type is eliminated and the operation can be conducted with speed and accuracy. Making the type 45 with a hollow body, as herein shown and described, provides a comparatively light type and at the same time it possesses all the strength required.

The body of the type may be provided 55 with a nick H which serves the double purpose of the ordinary nick to indicate the direction of the type and distinguish different fonts of the same body and also to receive the shoulder h on the type holder which holds the 60 type in place.

The shoulder c' where the web joins the top is preferably slanted as shown in Fig. 6 or rounded so that if the instrument or device employed to move the type should engage 65 the shoulder it will slide over and into the space E between the type.

Having thus fully described my invention, what I claim and desire to secure by Letters Patent is:—

A type having its body formed of two legs, a connecting web and a top, the shoulders formed at the joint of said web with the top being slanted or rounded, and said top being recessed between said legs to form an opening between each pair of type. 75

JOSEPH S. DUNCAN.
